UNITED STATES PATENT OFFICE.

HUGO TUECKMANTEL, OF IRVINGTON, NEW JERSEY, ASSIGNEE TO THE R. NEUMANN HARDWARE CO., A CORPORATION OF NEW JERSEY.

BAG-FRAME FASTENER.

1,247,182.

Specification of Letters Patent. Patented Nov. 20, 1917.

Application filed September 13, 1917. Serial No. 191,156.

To all whom it may concern:

Be it known that I, HUGO TUECKMANTEL, a citizen of the United States, residing at Irvington, in the county of Essex and State 5 of New Jersey, have invented certain new and useful Improvements in Bag-Frame Fasteners; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification.

15 This invention relates, generally, to improvements in frame-fasteners or retaining devices for holding the hinged sections of bag-frames or the like in their closed relation; and, the present invention has reference, more particularly, to that class of bag-frame fasteners comprising a spring-contained casing mounted upon one of the frame-sections, and an oscillatorily disposed locking element controlled by the spring for 20 maintaining the retaining ears of the locking element in their vertically disposed engaging relation with the two frame-sections of the closed bag-frame, or for maintaining said ears in their angularly raised relation 25 to permit the frame-sections to be brought into their opened relation.

The present invention has for its principal object to provide in connection with the shell or casing and the locking element of 30 the device, a closing plate out of which the spring which engages the shank of the locking element is forced or struck up by means of a suitable die, so as to dispense with the additional expense and labor in separately 35 riveting the spring in place; and, the invention has for its further object to provide a novel means for securing the said spring-provided closing plate in its position within the said shell or casing, and also for 40 securing the assembled parts upon a frame-section.

Other objects of the present invention not at this time more particularly enumerated will be clearly understood from the following detailed description of the present invention.

With the various objects of the present invention in view, the said invention consists, primarily, in the novel bag-frame fastener hereinafter set forth; and, the invention consists, furthermore, in the novel

arrangements and combinations of the several parts which comprise the fastener, all of which will be more fully described in the following specification and then finally embodied in the clauses of the claim which are appended to and which form an essential part of the said specification.

The invention is illustrated in the accompanying drawings, in which:

Fig. 1 is a side elevation of a bag-frame fastener made according to and embodying the principles of the present invention, showing the locking ears thereof in their locking relation with the closed frame-sections of a bag-frame, fragmentary portions of said frame-sections being represented in elevation.

Fig. 2 is a bottom view of the bag-frame fastener before the same is secured in its operative relation upon one of the frame-sections of the bag-frame.

Fig. 3 is a central longitudinal vertical section of the bag-frame fastener and the closed frame-sections represented in said Fig. 1; and Fig. 4 is a transverse vertical section, said section being taken on line 4—4 in said Fig. 1, looking in the direction of the arrow *x*.

Similar characters of reference are employed in the said above described views, to indicate corresponding parts.

Referring now to the said figures of the drawings, the reference-characters 1 and 2 indicate fragmentary portions of the two hinged frame-sections of a bag-frame of any suitable construction, one of said frame-sections, as 2, being adapted to be closed within the other frame-section, in the usual and well-known manner. The frame-sections here shown are of the L-shaped cross-section, but it will be evident that the bag-frame fastener is equally as well adapted to other constructions of bag-frames.

The reference-character 3 indicates a complete bag-frame fastener embodying the principles of the present invention, the same comprising a main shell or casing which consists of a top 4, side-walls 5 and end walls 6, all arranged to provide a chambered open-bottom element, substantially as shown.

The inner end-portions of the said chambered shell or casing are left solid, as at 7 and 8, but said solid parts extend only far enough so as to leave the recessed portions 9 and 10, surrounded on three sides, each,

- by the marginal edges of parts of the said side-walls 5 and the respective end-walls 6. The said solid portions 7 and 8 are each provided with rivet-posts, as 11 and 12, preferably integrally connected with said solid portions, and arranged substantially as shown in Figs. 2 and 4 of the drawings, the rivet-posts 11 being of greater length than the rivet-posts 12.
- 10 The closing plate herein-above mentioned is indicated by the reference-character 13 and is provided at its respective ends with perforations or holes 14 and 15. As shown in the several figures of the drawings, the 15 respective end-portions of the said closing plate are disposed within the respective recessed portions 9 and 10, with the respective rivet-posts 11 and 12 extending into and through the respective perforations or holes 20 14 and 15, the short rivet-posts 12 having their projecting ends riveted over so as to provide heads 16, and whereby, as will be clearly evident, the said spring-provided closing plate 13 is securely fastened in its 25 closing position over the open part of the main shell or casing of the device. As shown in Figs. 2 and 3 of the drawings, the said closing plate 13 is formed with a longitudinally and inwardly extending spring-tongue 17, which is struck out of said plate by means of a suitable die, and is integrally connected with said plate, as at 18. The main shell or casing is formed in its side-walls 5 with the usual openings 19, in which 30 35 are oscillatorily disposed the shank-portions 20 of the locking element which is provided with the usual locking ears 21 adapted to straddle the closed frame-sections in the usual manner.
- 40 Within the chambered portions of the said main shell or casing, and contiguous to the inner faces of the longitudinally extending side-walls 5, the said shank-portions 20 are preferably provided with annular shoulders, 45 as 22, to prevent lateral displacement of the said locking element, see dotted outline in Fig. 3 of the drawings, and intermediate of said shoulders 22 the locking element has a main shank-portion 23 of triangular or other 50 55 suitably formed angular cross-section, with which the spring-tongue is in engagement, so as to maintain the said locking element and its locking ears 21 in their various positions, as will be clearly evident.
- 55 The various parts of the bag-frame fastener being thus properly assembled, the rivet-posts 11 are passed through correspondingly placed holes or perforations 24 in the frame-section 1, and the free ends of 60 said posts riveted over, as at 25, for securing the device in its operative position upon the upper surface of said frame-section.

The operation of the device will be clearly

understood from the foregoing description and from an inspection of the drawings and 65 need not, therefore, be further described.

I claim:—

1. A bag-frame fastener comprising a chambered shell, a locking element rotatably mounted with relation to said shell and having a shank-portion extending across the chamber of said shell, a closing plate secured to said shell and extending across the opening of said shell, and a spring-tongue struck out of said closing plate, said spring-tongue extending upwardly into the said shell into engagement with the shank-portion of said locking element. 75

2. A bag-frame fastener comprising a chambered shell, a locking element rotatably mounted with relation to said shell and having a shank-portion extending across the chamber of said shell, said shell being provided with solid end-portions and receiving recesses, a closing plate extending across the opening of said shell, said plate having its ends disposed in the said receiving recesses, means extending from said solid end-portions and secured to the ends of said closing plate, and a spring-tongue struck out of said closing plate, said spring-tongue extending upwardly into the said shell into engagement with the shank-portion of said locking element. 85 90

3. A bag-frame fastener comprising a chambered shell, a locking element rotatably mounted with relation to said shell and having a shank-portion extending across the chamber of said shell, said shell being provided with solid end-portions and receiving recesses, a closing plate extending across the opening of said shell, said plate having its ends disposed in the said receiving recesses, said closing plate being provided in each end-portion with a pair of perforations, a pair of rivet-pins projecting from each solid end-portion of said shell, each pair of rivet-pins extending into and through a pair of said perforations in each end-portion of the closing plate, one of said rivet-pins being riveted to said closing plate and the other rivet-pin of each pair of pins extending beyond said closing plate for riveting to a section of a bag-frame, and a spring-tongue having a portion extending upwardly into the chamber of said shell into engagement with the shank-portion of said locking element. 95 100 105 110 115

In testimony, that I claim the invention set forth above I have hereunto set my hand this 8th day of September, 1917. 120

HUGO TUECKMANTEL.
